UNITED STATES PATENT OFFICE.

GEORGE ROCKWELL, OF MERIDEN, ASSIGNOR TO ROGERS & BROTHER, OF
WATERBURY, CONNECTICUT.

DESIGN FOR A HANDLE FOR SPOONS, &c.

SPECIFICATION forming part of Design No. 23,172, dated April 10, 1894.

Application filed March 12, 1894. Serial No. 503,369. Term of patent 7 years.

To all whom it may concern:

Be it known that I, George Rockwell, of Meriden, in the county of New Haven and State of Connecticut, have invented a new Design for the Handles of Spoons, Forks, &c.; and I do hereby declare the following, when taken in connection with the accompanying drawing and the letters of reference marked thereon, to be a full, clear, and exact description of the same, and which said drawing constitutes part of this specification and represents a face view.

This invention relates to a design for the handles of spoons, forks, &c., and the design consists in the configuration and ornamentation of the handle as hereinafter described and shown in the accompanying illustration.

The handle contracts from its junction with the bowl slightly, then gradually expands toward the tip, its lower end

bowl in a series of ribs *a*, which die out in the narrower portion *c* of the handle, and again branch out where the narrower portion of the handle meets the tip. The upper portion *d* of the handle consists of a series of inwardly curved scrolls *e*, inclosing a plain panel *f*, and surmounted by a shell-like ornament *g* forming the tip of the handle, all as shown in the accompanying illustration.

I claim—

The design for the handles of spoons, forks, &c., as described and shown in the accompanying illustration.

In testimony whereof I have signed this specification in the presence of two subscribers,

GEO. ROCKWELL.
